COLOR SCREEN FILM AND PROCESS FOR MANUFACTURING THE SAME

Application filed November 8, 1926, Serial No. 147,117, and in Germany November 23, 1925.

It is known to manufacture screen elements for the purposes of color photography, for instance by atomizing colored solutions in which a more or less quickly volatilized liquid is used as the solvent, and a colloid as the remaining solid body.

Glass screens are further known in which the support and the screen elements are constituted by glass. In such a case a rigid screen 10 is formed.

On the contrary, this invention relates to screens with a flexible support, that is to say to color screen films, and consists in the screen elements and their flexible support being constituted by colloids with identical mechanical and optical properties, for instance by one and the same colloid. In any case, the supports and the screen elements should be soluble in one and the same solvent. The following results will be obtained thereby:

1. An exceedingly thorough, insoluble connection between the flexible support and the screen elements is produced.

2. Any deviation in the travel of rays between the support and the screen element is avoided, as both have the same coefficient of refraction; the picture will therefore remain unaffected in the event of the plane of separation between the film and the screen layer 30 being deformed by the process of securing the screen elements to the film.

3. No new difficulties are experienced in putting on the layer sensitive to light. On the contrary, it has been found even that the 35 said layer adheres to the screen layer without employing the hitherto usual adhesive. The solvents hitherto used for nitro-cellulose or acetyl-cellulose, can be used, such as acetone, glacial acetic acid, ether-alcohol mixtures singly or in mixtures with each other.

Fig. 1 is a diagrammatical view of a form of apparatus for carrying out the process;

Fig. 2 is a cross section of a film with the flattened powder grain;

Fig. 3 a view similar to Fig. 2 of the modified process in which the powder grains are first applied to the web;

Fig. 4 shows the transfer of the powder grain from the web to the carrier; and

Fig. 5 shows a cross section of the film with

the spherical grain before passing between pressure rollers.

The manufacture of the new color screen film can be effected either by putting on the screen elements directly on the flexible colloid support, or by preparing them first on a web of paper or metal and then transferring them to the flexible colloid support, for instance by the transfer process. This latter process has the advantage that the screen elements can 55 be easily "ironed" or smoothed or levelled at the top and at the bottom.

In the appended drawings I have shown diagrammatically in Fig. 1, a form of apparatus which may be used to carry out my process and in Figure 2 I have shown an enlarged cross-section, a part of a color screen film made in accordance with my process.

Referring to Figure 1, *b* is a roller or spool carrying film *a* to be treated. *d* and *d'* are 70 guide rollers, the latter being immersed in liquid contained in receptacle *e*. A guide roller *d*² guides the film out of the receptacle *e* and rollers *l'* and *l* pull the film past the powder receptacle *f* containing powder which 75 issues from the receptacle *f* through the screen or sieve *g*. The film, after receiving a coating of powder, consisting of spherical-shaped grains *n'*, Fig. 5, passes the roller *h* and brush *i*, the latter brushing off excess powder. 80 The suction pipe *k* removes any grains which do not adhere to the film and, after passing rollers *l'* and *l*, the former being heated, is wound up on *c*.

The liquid contained in receptacle *e* is one which has the property of softening the film superficially, such liquids being known. The screen powder is mixed in the correct color ratio and is applied immediately after the film is softened. The rollers *l'* and *l* place 85 the coated screen under pressure so as to flatten as at *n* the previously spherical grains and the heated roller *l'* softens the grains to some extent so as to facilitate flattening.

Experience has shown that with this process of working, the grains though slightly flattened as regards their shape, cover the support without any gaps and without overlapping each other. The film thus covered with a screen, is wound up at the end of the 90 100

machine, in order subsequently to be coated with a layer sensitive to light, and then cut up.

5 Figure 2 shows the film in cross-section, *m* being the carrier and *n* the flattened powder grains while *n'* in Fig. 5 shows the spherical grain previous to flattening.

10 Fig. 3 shows a paper or metal web *o* to which the screen film *n* is first applied as described with regard to Figures 1 and 2 and flattened thereon. Subsequently, according to the transfer process the screen film *n* is attached to the support *m* and the paper or metal web *o* removed, as shown in Fig. 4 15 of the drawing.

20 Fig. 5 shows the condition of the film before it passes between the rollers *l* and *l'*, and Fig. 2 shows the flattened condition of the grain after the film has passed between said rollers.

25 Having now particularly described and ascertained the nature of my said invention and in what manner the same is to be performed I declare what I claim is:—

30 1. A process for the manufacture of a color screen film consisting of a supporting colloid and colloidal screen elements the original spherical shape of which is flattened, wherein the supporting colloid is provided with a layer of screen grains and the whole then passed between pressure rollers, of which the roller acting on the screen grains is heated.

35 2. A process for the manufacture of a color screen-film comprising a colloid support and colloid screen elements, said elements consisting of grain with flattened surfaces; the steps of the process consisting in first applying spherical colloid grain to a web, then flattening the grains on the web and lastly transferring the flattened grain to the colloid support.

40 3. A process for the manufacture of endless color screen films whose screen elements consist of a colloid and are applied directly to the film consisting of a colloid of the same mechanical and optical properties as the screen elements, preferably from the same colloid and are compressed by applying pressure and heat, said colloid support provided with the screen elements in a single layer being passed between two pressure rollers, of which the roller acting on the screen grains is heated.

45 55 In testimony whereof I affix my signature.
RUDOLF RUTH.
